VALVE LIFTER

Application filed January 17, 1931. Serial No. 509,353.

This invention relates to a valve lifter whereby the valves of an internal combustion engine are so acted upon as to make them readily accessible for grinding or replacement.

An object of our invention is to provide a novel, reliable and simple means for the removal and replacement of valves in internal combustion engines, and the like.

Another object is to provide a novel valve lifter which will allow the valves to be cleaned, ground, or removed without removing the valve spring from its position about the valve stem, and without the removal of the valve lifter assembly.

Still another object is to provide a novel valve lifter in which there is less danger to the workman, that is, he is less likely to injure his fingers by the sudden expansion of the valve spring due to the failure of the valve lifters heretofore in use to properly grip the spring.

An advantage of our invention is to provide a valve lifter of the character stated in which the valve spring keeper is readily accessible for removal.

A further advantage of our invention resides in the overhead raising of the valve prior to holding the spring compressed.

Other objects, advantages, and features of invention may appear from the accompanying drawing, the subjoined detailed description, and the appended claims.

In the drawing

Figure 1 is a fragmentary, vertical, sectional view of an engine block with our valve lifter in operative position.

Figure 2 is a front elevation of the valve spring support.

Figure 3 is a top plan view of the same.

Figure 4 is a side elevation of the valve raiser.

Figure 5 is a bottom plan view of the same.

Figure 6 is a fragmentary, bottom plan view of a modified form of valve lifter.

Figure 7 is a sectional view taken on line 7-7 of Figure 6.

Figure 8 is a vertical sectional view of an

engine head with the valve lifter shown in Figure 6 in operative position thereon.

Figure 9 is a front elevation of a modified form of spring support.

Figure 10 is a perspective view of the support shown in Figure 2.

Figure 11 is a perspective view of the support shown in Figure 9.

Referring more particularly to the drawing, the numeral 1 indicates an engine block 60 of the L- or T-head type, which includes a valve 2, a spring 3 surrounding the valve stem and normally urging said valve against its seat, a cam shaft 4, and a cam follower 5.

In valve lifters heretofore in use, the valve 65 spring was first compressed by a part of the valve lifter which engaged the bottom of the spring, the keeper was then removed, the valve lifter was released, and the spring was then removed from around the valve stem.

This required considerable time, and with our lifter we eliminate the extra work and hazard of removing the valve spring from the block.

When starting to grind the valves or replace the same, the cam shaft 4 is caused to rotate, and one of the valves is raised in the usual and well-known manner. Our raising tool 6 is then applied and this tool consists of a handle 7 which extends from, and is integral with a pair of spaced fingers 8-8.

The spaced fingers extend on either side of the valve stem and engage the head of the valve, as shown in Figure 1. After the raising tool 6 has been inserted under the head 80 of the valve, the cam shaft 4 is rocked back so as to leave the follower 5 free to drop away from the valve stem. The tool 6 is then operated to lift the valve 2 upwardly, which compresses the spring 3. This operation is 85 accomplished by swinging the handle 7 downwardly in an arc which causes the tool to rock on the curved portion 9 at the rear of the fingers 8-8. The spaced fingers are so arranged that the seat on the valve head can- 90 not be scratched.

The spring support 10 is now inserted between the bottom of the spring 3 and the top of the cam follower 5, as shown in Figure 1, or between the follower lock nut, the base, 100

or the followers. The spring support consists of a semi-cylindrical body 11 which terminates in an inwardly directed arcuate flange 12 on the top thereof. The spring 3 rests on this flange during the valve grinding or replacing operation.

A wall 13 is integrally formed on the bottom of the support 10, and this wall is provided with a notch 14. The purpose of this notch is to receive any projecting part of the cam follower 5. When the spring 3 has been fully compressed, in a manner previously described, it is a relatively simple matter to insert the spring support in the manner shown in Figure 1. The handle 7 is then released and the valve is free to drop upon its seat and can be ground or reseated as necessary. To remove the support 10, we provide a rib 15 which is integrally formed in the body 11, and a hook is inserted around this rib and the support jerked out after the valve is ground.

The spring supports 10 are made in various diameters and various lengths to fit different types of L- and T-head engines. For the overhead type of engine, we provide a spring compressor as shown in Figures 6 to 8 inclusive. This type consists of a handle 16 on one end of which a head 17 is integrally formed. A link 18 is mounted in the head 17 as follows: A slot 19 extends longitudinally in the head 17, and the link 18 is formed with a transverse lug 20 on the top thereof, which lug extends across the slot 19. A plurality of holes 21 is formed in the link 18, and one of these holes fits over a stud 22 which extends from the head 23, and the spring 25 surrounds the valve stem and urges said valve on to its seat.

A block 26 is placed in the combustion chamber when the head is on the bench to keep the valve from dropping down. The head 17 is also provided with a circular recess 27 which receives the top of the spring 25. An opening 28 is provided through the head 17 so that the valve stem can project therethrough. The valve lifter is arranged as shown in Figure 8 and pressure is exerted on the handle 16. The spring 25 is thus compressed and the valve spring keeper in the end of the stem can be quickly and easily removed. The spring compressor is then released, and the spring is removed.

In the modified form of spring support shown in Figure 9, the usual semi-cylindrical body 11 is provided, as previously described. The arcuate flange at the top and the wall at the bottom of the body may be detachable, that is, the bottom wall 30 is formed with a pair of side fingers 31-31 which grip the body of the support, and a third finger 32 extends into a hole 33 which is formed in the body. Thus the bottom wall is securely held on the body and a cheaper construction is

provided than the type shown in Figures 2 and 3.

Having described our invention, we claim:

1. A valve tool comprising a semi-cylindrical body, an inwardly extending flange integrally formed on the top of said body, the valve spring being adapted to rest thereon, an inwardly extending wall on the bottom of said body, said wall having a notch formed therein into which the cam follower extends.

2. A valve tool comprising a semi-cylindrical body, an inwardly extending flange integrally formed on the top of said body, the valve spring being adapted to rest thereon, an inwardly extending wall on the bottom of said body, said wall having a notch formed therein into which the cam follower extends, and a rib integrally formed in said body whereby the tool is removed after the valve is ground.

3. A valve tool comprising a semi-cylindrical body, a bottom wall detachably secured to the body, fingers on said wall, said body having a hole formed therein, another finger on said wall, said last named finger projecting into said hole whereby the wall is held in position, and said wall having a notch formed therein.

4. A valve tool comprising a semi-cylindrical body, a bottom wall detachably secured to the body, fingers on said wall, said body having a hole formed therein, another finger on said wall, said last named finger projecting into said hole whereby the wall is held in position, and said wall having a notch formed therein, and an inwardly extending flange integrally formed on the top of said body.

In testimony whereof, we affix our signatures.

WALTER L. ZIEGLER.
JOSEPH W. DURNELL.
